MECHANICAL WIG HOLDER

BACKGROUND OF THE INVENTION

This invention relates to a device for holding a wig, and, more particularly, to a device for supporting a wig so that it may be treated.

Head forms are generally used by beauticians for supporting a wig, or any other type of hair piece, so that it may be treated by cleaning, setting, coloring, or combining, etc. Normally the wig is secured to the form by inserting small metal "T" pins through the wig and its net base, and into the form, which is usually of canvas. However, after the wig is treated it must be removed from the form by reaching through the wig to remove the "T" pins, which often messes up the treated wig. This problem is compounded when, as in normal practice, the wig, after removal from the beauticians form, is placed on a styrofoam head form to be taken home by the customer, since the above procedure must be repeated. Therefore, in both cases the wig must be recombed or reset after removal from the forms, which, of course, is very inconvenient.

SUMMARY OF THE INVENTION

It is therefore an object of the present invention to provide a mechanical wig holder which enables a wig, or any other type of hair piece, to be supported for treatment, without danger of the treated wig being ruined.

Briefly summarized, the mechanical wig holder of the present invention comprises a housing adapted to be carried by a head form, catch means mounted for pivotal movement with respect to the housing, and control means carried by the housing for controlling the movement of the catch means between an operative position in engagement with the wig and an inoperative position.

BRIEF DESCRIPTION OF THE DRAWINGS

Reference is now made to the accompanying drawings for a better understanding of the nature and objects of the wig holder of the present invention, which drawings illustrate the best mode presently contemplated for carrying out the objects of the invention and its principles, and are not to be construed as restrictions or limitations on its scope. In the drawings:

FIG. 1 is a perspective view of the wig holder of present invention;

FIG. 2 is a front elevational view of the wig holder of the present invention;

FIG. 3 is a transverse sectional view taken along line 2-2 of FIG. 1;

FIG. 4 is a horizontal sectional view, taken along the line 4-4 of FIG. 3; and

FIG. 5 is a perspective view showing the wig holder of the present invention mounted on a head form.

DESCRIPTION OF THE PREFERRED EMBODIMENTS

Referring specifically to FIGS. 1 and 2 of the attached drawings, which depict the mechanical wig holder of the present invention, the reference numeral 10 refers, in general, to a housing which may be of any type material such as plastic or metal, and which includes a pair of end plates 12 and 14, a pair of side plates 16 and 18, and a curved top 20. It is understood that the housing may also be provided with a bottom which may be fixed or slidable in and out of position.

As shown in FIG. 3, a pair of longitudinal shafts 22 and 24 are rotatably mounted in holes provided in the end plates 12 and 14, and have checknuts 26 and 28, respectively, mounted on one of their ends, and a pair of turning knobs 30 and 32, respectively, mounted on the other of their ends to rotatably secure the shafts with respect to the housing. A pair of transverse shafts 34 and 36 are rotatably mounted in holes formed in the side plates 16 and 18, the shaft 34 being fitted with checknuts 38 and 40 at each end thereof, and the shaft 36 being similarly fitted with checknuts 42 and 44.

A bevel gear 50 is secured, in any known manner, to the shaft 22 and is positioned to mesh with a corresponding bevel gear 52 secured onto the shaft 34 so that rotation of the shaft 22, via knob 30, imparts a corresponding rotation to the shaft 34. Likewise, a bevel gear 54 is secured to the shaft 24 and meshes with a bevel gear 56 secured to the shaft 36 so that rotation of the knob 32 causes a corresponding rotation of the shaft 36.

As shown in FIGS. 2-4, a pair of catch pins 60 and 62 are secured, in any known manner, into a pair of bores provided in the shaft 34, and a pair of catch pins 64 and 66 are likewise secured with respect to the shaft 36. Each of the catch pins has a straight portion secured to its respective shaft and a free curved portion, the curved portion of the pins 60 and 64 extending outwardly through a slot 68 formed in the cover 20, and the curved portion of the pins 62 and 66 extending outwardly through a similar slot 70 in the operative position of the pins, as better shown in FIG. 1. It is noted that, in the latter position, the curved portions of the pins 60 and 62 extend towards the end plate 12, and the curved portions of the pins 64 and 66 extend towards the end plate 14.

In operation, the device is placed in a head form, such as shown in FIG. 5 by the reference numeral 70, by inserting the housing 10 into a notch 72, or the like, formed in the form, so that the curved cover 20 extends slightly below or coextensive with the adjacent surfaces of the form. The knobs 30 and 32 are rotated so that the pins 60, 62, 64, and 66 are pivoted into a retracted position in the housing 10 as shown at 62a and 66a in FIG. 2, and the wig or hair piece is placed over the head form 70 by attaching a portion of the former to catch member 74, or the like, fixed to the latter, and fitting the wig in a normal position over the head form.

The knobs 30 and 32 are then rotated so that the catch pins 60 and 62 move outwardly through the slots 68 and 70, respectively, in a direction towards the end plate 12, and the pins 64 and 66 move outwardly through the same slots towards the end plate 14 into their extended positions as shown in FIGS. 1 and 2. In so moving, the curved portions of the pins pass through the net base, or the like, of the wig and therefore secure same with respect to the head form 70 so that the wig may be treated. Of course, after the wig has been treated it can be removed from the base by reversing the above process.

It is understood that in arrangement wherein the customers are provided with an additional head form for the wig, a wig holder similar to the one just discussed may be provided in the latter and the same operation repeated.

It is understood that several variations of the mechanical wig holder disclosed above can be made within the scope of the invention. For example, although in the above arrangement the curved portion of the catch pins pass through the slots at approximately the same lengthwise position of the latter, it is understood that the shape of the pins and their mounting with respect to the shafts may be varied so that the pins may move lengthwise with respect to their respective slots during movement from their retracted position to their operative position. Also, a larger number of catch pins can be provided, in which case a corresponding number of slots would be provided through the cover member 20 of the housing 10. Further, the longitudinal shafts 22 and 24 may be eliminated along with the bevel gears, and the knobs 30 and 32 placed on the shafts 34 and 36, when the shape of the head form permits.

Of course, other variations of the specific construction and arrangement of the wig holder disclosed above can be made by those skilled in the art without departing from the invention as defined in the appended claims.

We claim:

1. A device for securing a hair piece on a head form, comprising a housing adapted to be inserted within a notch provided in said form and having an outer surface adapted to extend substantially coextensive with an outer surface of said form, at least one pin mounted for pivotal movement with respect to said housing, and control means carried by said

housing and operatively connected to said pin for controlling the movement of said pin between an operative position wherein a portion of said pin extends outwards from said housing in engagement with said hair piece and an inoperative position wherein said pin extends within said housing, said pin having a straight portion fixed to said control means and a curved portion for engaging said hair piece, said curved portion being adapted to extend through a notch formed in said surface of said housing in said operative position.

2. A device for securing a hair piece on a head form, com-

prising a housing adapted to be carried by said form, catch means mounted for pivotal movement with respect to said housing, shaft means rotatably mounted in said housing and operatively connected to said catch means for controlling the movement of said catch means between an operative position in engagement with said hair piece and an inoperative position, and a control knob fixed to said shaft means externally of said housing.
